UNITED STATES PATENT OFFICE.

SPENCER C. CARY, OF BROOKLYN, NEW YORK, ASSIGNOR TO CARY MANUFACTURING CO., OF BROOKLYN, NEW YORK, A CORPORATION OF NEW YORK.

BUNDLED WIRE.

1,427,519.

Specification of Letters Patent. Patented Aug. 29, 1922.

Application filed June 14, 1922. Serial No. 568,116.

To all whom it may concern:

Be it known that I, SPENCER C. CARY, a citizen of the United States, residing at the city of New York, borough of Brooklyn, county of Kings, and State of New York, have invented a certain new and useful Bunched Wire, of which the following is a specification.

This invention pertains to wire in bunched condition, the end portion of which bundle is encased to accord protection to the individual wires in a manner to preclude distortion of said individual wires which may result from service conditions.

15 The object is to attain security in the retention of the encasing means with a view to precluding the displacement of said encasing means with respect to the bundle and the individual components thereof.

20 According to the invention, a fastening member passes transversely through the bundle and through the encasing means therefor, and this member is in fixed relation to the encasing means so as to retain 25 the same securely upon the bundle end.

In a practical embodiment of the invention, the encasing means is a cap composed of compressible material, around which cap is wrapped a part of the fastening member 30 in such manner as to compress said cap into fixed relation to the bundle.

The cap for encasing the bundle end is composed, preferably, of sheet metal formed up to produce a shell and a head integral 35 one with the other, and in order to attain the desired compressible formation of said cap, the shell thereof is cut or slitted, said slits extending from a free edge of the shell inwardly thereof to a desired point.

40 The fastening member is positioned within the end portion of the bundle transversely to said bundle, and it extends through the shell of the encasing cap, the ends of said fastening member being passed 45 or wrapped around the slitted shell of the cap and the free ends secured firmly together. In wrapping the ends of the fastening member around the slitted shell of the cap, said fastening member is drawn 50 tightly for the purpose of compressing the shell of the cap into tight frictional contact with the end portion of the bundle.

It may be added that the encasing means and the fastening therefor are useful in connection with a bundle each wire of which is

deformed by producing a flattened portion and a shoulder thereon, and upon assembling wires of this formation into a bundle, the flattened deformed portions thereof have a tendency to somewhat enlarge the end portion of the bundle. The encasing cap slit 60 as described may be slipped with facility over the expanded end portion of the bundle, and by wrapping the fastening member tightly around the cap below the 65 shouldered portion of the wires, said cap is compressed in a manner to utilize the shouldered wires as a means for preventing end-wise displacement of the cap on the bundle end. 70

Other functions and advantages of the invention will appear from the following description taken in connection with the drawings, wherein—

Figure 1 is a view in side elevation showing straightened wires assembled to produce a bundle and with an encasing cap applied to the respective end portions of said bundle. 75

Figure 2 is a vertical longitudinal section through an end portion of the bundle, the encasing means therefor, and the retaining member for said encasing means. 80

Figure 3 is a transverse horizontal section in the plane of the dotted line 3—3 of Figure 2. 85

Figure 4 is a vertical longitudinal section through an end portion of a wire bundle, illustrating another embodiment of the encasing means for the bundle end. 90

Figure 5 is a detail perspective view of another form of the slitted cap.

In this art it is common practice to draw wire at a mill, and to coil or wind said wire into a bundle, in which condition the wire is shipped from the mill to the consumer. Wire so coiled or wound cannot be used to advantage in binding shipping packages with wire, for the reason that the curvature imparted to the wire by the winding operation has a tendency to loop the wire when passed around a package. In view of such condition of the wire the practice is to preliminarily straighten the wire by subjecting it to the action of a straightening machine, and in this straightening operation said wire is cut in pieces or lengths suitable for use on packages of a certain size. The straightened and cut pieces of wire, uniform as to length, are assembled 105 110

into parallel relation to compose the bundle. In some instances, the straightened and cut pieces of wire are deformed by a swaging operation to produce on each wire a flattened 5 and shouldered portion, the same being useful in connection with certain forms of tensioning implements for the reason that the flattened portion of the wire may be easily introduced into the implement and the 10 shoulder of the wire co-operates with said implement to prevent slipping of the wire when tension is applied thereto. The individual wires are indicated at A, and the deformed portion thereon is shown at a in 15 Figures 2 and 4 of the drawings.

The wires are straightened, cut to length, and deformed at a, after which a desired number of such wires are assembled into parallel relation to compose the bundle 20 shown in Figure 1 and partly represented in Figures 2 and 4. When bundled, the wire is shipped to the individual users, such as packing houses, merchants, and others, and in the course of shipment, or in the 25 storage of the wire, it must be handled, so that under such conditions of service, the end portions of the individual wires may become bent, twisted or otherwise distorted, making it a more or less difficult operation 30 to use the wire in connection with a tensioning implement.

In order to protect the wires from distortion under service conditions, I employ encasing means in the form of a cap B which 35 is applied to the end portion of the bundle so as to cover the ends of the individual wires and the deformed portions a thereof, see Figures 2 and 4. This cap is composed of any material suitable for the purpose, 40 but it is preferred to employ sheet metal in the manufacture of the cap, the metal being formed in a well known manner to produce a shell b and a head c in one integral piece. As shown in Figures 3 and 5 of the drawing, the shell b of the cap is slotted 45 or cut at d, the slits extending inwardly from an edge portion of the shell and for a suitable distance. The slits d may be on lines parallel to the vertical longitudinal axis of the cap, as shown in Figure 5, but it is preferred to incline the slits d at an angle to said vertical longitudinal axis, in order that the slotted shell may be compressed to a desired extent without an overlap 50 in the edges of the metal due to a reduction in the diameter of the cap shell when it is compressed.

C is the fastening member extending 60 through the end portion of the bundle and the encasing means therefor, said fastening member being so related to the cap as to compress the latter into tight frictional contact with the wires composing the bundle at the end thereof. This fastening member 65 is shown as a wire, or other flexible material,

inserted through the middle portion of the bundled wire, below the deformed portions of said wires. One end of the fastening wire is passed in one direction around the outside of the cap, as at c', whereas the other end portion of said fastening wire is passed in an opposite direction, as at c'', around the outside of the cap, said two end portions of the wire being brought together and twisted as at d', see Figure 3. By 70 wrapping the end portions of the fastening wire around the slotted shell of the cap, and by drawing said wire tightly in contact with said slotted shell, the wire operates to compress the slotted shell so that it will 75 have the desired frictional contact with the wires of the bundle adjacent the end thereof. The fastening wire is positioned below the deformed portions of the wires composing the bundle, and the shell of the cap is compressed into tight contact with said bundle and below said deformations of the wires, as a result of which the cap is applied securely to the bundle of deformed wires, and cannot become displaced on said bundle 80 lengthwise thereof, for the reason that the bundle at the deformed portions of the wires is of a diameter exceeding the diameter of that part of the cap which is compressed by wrapping the fastening wire exteriorly 85 upon the cap, hence the cap can be displaced only with difficulty and is not removable until the fastening wire is purposely cut so as to free said cap preliminary to its removal from the bundle end.

Of course, the encasing means and the fastening wire therefor are adapted for, and may be used in connection with bundled wire the wires of which are not deformed, i. e., with a bundle composed of straightened and 105 cut wires free from the deformations a. In this event, the slotted cap is applied to the end portion of the bundle to encase the end portions of straight wires, and the fastening wire is passed through the bundle and the 110 cap, the end portions of said fastening wire being wrapped around, and drawn tightly into contact with, the slotted shell of the cap so as to compress said slotted shell into tight frictional contact with the bundle. By 115 passing the fastening wire transversely through the bundle and the cap, said wire becomes anchored, in a measure, within the bundle by reason of the frictional contact of said wire with the individual wires which are in a more or less compressed or compacted condition at the end portion of the bundle, and with the fastening wire intact, the encasing cap is so firmly applied to the bundle end that it cannot be displaced under the ordinary service conditions of the bundled wire.

D is a liner positioned within the imperforate head, c, of the cap, and in abutting relation to the ends of the individual compo- 120

nents of the bundle. This liner is composed of a relatively soft material such as felt, paper, card board, or other material of a fibrous nature. The liner is confined within 5 the encasing means between the imperforate head *c* thereof and the ends of the individual wires, and the utility of the liner is to protect the head of the encasing means from becoming perforated under the impact of the 10 wires should the bundle be dropped on end, as sometimes occurs in handling the bundle in the stages between storage and shipment of the wire.

As shown in Figures 2 and 3 of the drawing, 15 the fastening wire is used to compress the slotted portion of the cap, but in Figure 5 the cap is shown as having an annular groove, *e'*, in the slotted part of its shell. This groove is adapted for the reception of 20 the fastening wire when wrapped around the shell, and said groove affords shoulders against which the wrapped wire lodges, whereby the groove contributes to the security of the attachment of the fastening 25 wire, for the reason that it tends to preclude dislodgment of the wire with respect to the cap, hence the grooved cap and the wrapped wire co-operate in attaining a fixed and non-displaceable relation of the cap to the bundled 30 wire.

It is not desired to limit the invention to the use of a cap in conjunction with a fastening wire wrapped around said cap, for the reason that the cap may be contracted at 35 its inner edge around the bundle by means other than the use of the fastening wire. In Figure 4 there is shown a metallic cap *E* comprising an imperforate shell and an imperforate head, said cap being applied to the 40 end portion of the bundle composed of deformed wires, as heretofore described. This cap is reduced in diameter below the expanded portion of the bundle produced by the deformed wires, and this reduction in the 45 diameter of the cap shell below said deformed wires is brought about by the application of pressure to the lower free edge of the cap shell so as to deflect or crimp said edge inwardly at *e*. This crimped edge of 50 the cap shell co-operates with the deformed wires to preclude displacement of the cap relatively to the end of the bundle, thus simplifying the construction by omitting the fastening wire. It may be stated, however, 55 that I consider the fastening wire used in conjunction with the slotted shell as the preferred construction.

Having thus fully described the invention, what I claim as new and desire to secure 60 by Letters Patent is:

1. Bundled wire comprising individual pieces uniform as to length and assembled into parallel relation, encasing means upon an end portion of the bundle, and a fastening member extending transversely within

said end portion of the bundle and secured in fixed relation to said encasing means.

2. Bundled wire the end portion of which is covered by encasing means, and a fastening member extending within the end portion of the bundle, said fastening member being in contact with and compressing said encasing means about the ends of the wires. 70

3. Bundled wire the end portion of which is covered by encasing means, and a fastening member extending transversely within an end portion of the bundle and contacting exteriorly with said encasing means for contracting the latter into a desired frictional contact with said end portion of the bundle. 75

4. Bundled wire composed of individual pieces of wire uniform as to length, a compressible encasing means for the end portion of said bundle, and fastening means in contact with the encasing means exteriorly 85 thereof, said fastening means extending transversely within the bundle.

5. Bundled wire the end portion of which is encased by a cap, and a fastening member in encircling contact with and compressing the cap exteriorly thereof, whereby the cap is confined into frictional contact with 90 said end portion of the bundle.

6. Bundled wire comprising individual pieces of deformed wire assembled into parallel relation, and compressible encasing means upon an end portion of said bundle, said encasing means being compressed into frictional contact with the bundle below the deformed portions of the individual wires. 95

7. Bundled wire comprising individual pieces of deformed wire assembled into parallel relation, compressible encasing means positioned upon the bundle end and covering the deformed wires, and means in contact with the encasing means and operating to compress said encasing means into frictional contact with the wires below the deformations thereof. 105

8. Bundled wire comprising individual 110 pieces of deformed wire assembled into parallel relation, a cap composed of compressed material, said cap being positioned on the end portion of the bundle to encase the deformations of the individual wires, and a 115 fastening member one part of which extends within the bundle and through the cap, said fastening member having another portion or portions wrapped exteriorly around the cap and in contact therewith. 120

9. Bundled wire comprising pieces assembled in parallel relation, a slotted cap fitted upon an end portion of the bundle, and a fastening member extending within the bundle and wrapped upon the slotted 125 portion of said cap.

10. Bundled wire comprising individual pieces assembled in parallel relation, a slotted and grooved cap fitted upon an end portion of the bundle, and a fastening wire po- 130

sitioned within the groove of the cap and having frictional contact with the slitted portion thereof for compressing said cap into frictional contact with the bundle.

5. 11. Bundled wire comprising individual pieces substantially uniform as to length, and encasing means positioned upon an end portion of the bundle, that portion of the

encasing means remote to the extreme end of said bundle being contracted upon the bundle and into frictional contact therewith.

In testimony whereof I have signed my name hereto this 13th day of June, 1922.

SPENCER C. CARY.
